PERFORATING MACHINE

Karl Nicolay, Bielefeld, Germany, assignor to
Duerkoppwerke Aktiengesellschaft, Bielefeld,
Germany, a German company

Application May 26, 1950, Serial No. 164,493

Claims priority, application Germany June 9, 1949

9 Claims. (Cl. 164—89.5)

1

This invention concerns perforating machines. In the cutting rooms of modern clothing factories it is no longer customary to sketch separately on the material the individual portions of a suit or costume to be cut such as fronts, sleeves, collars, pockets etc., but the whole cutting plan, i. e., all the separate pieces of a garment or of several garments, are drawn on a sheet of paper corresponding to the size of the outspread length of cloth and then perforated along the cutting lines.

With this paper pattern it is then possible to transfer the whole cutting pattern to the length of material in one operation by blowing or rubbing suitable powder through the perforations.

Apparatus or machines are already in existence for perforating the patterns. Such machines operate with die and matrix and are stationary, and the forward movement of the paper to obtain the desired distance between the perforations is performed by a feed mechanism, movable in all directions.

Because of the size of the paper pattern and the (at times) sharply curved cutting lines running in all directions it is, however, difficult to work very quickly and to stamp the perforations exactly on the cutting lines as required. Furthermore, only round perforation holes can be produced. By another method it is possible to keep the paper firmly in place and burn out the perforations with an electrically heated disc, in appearance like a thin cogged or toothed wheel. For this, however, a special kind of paper is required, which again, has always proved to be a drawback.

It is an object of the invention to provide a perforating machine such that the drawbacks of the procedures mentioned above are avoided.

According to the present invention there is provided a perforating machine of the type guided by hand over a stationary pattern including a driving motor, a constantly revolving shaft driven by said motor, punch means for effecting penetration of said pattern, a spring disposed so as to be capable of imparting striking motion to said punch means, a cam mounted on said shaft and effective to control the movement of said punch means, and clutch means adapted to cause said cam to rotate with said constantly revolving shaft, there being provided a pivotally mounted lever the free end of which is adapted to follow the movement of said cam and in so doing to tension said spring prior to actuation of said punch means.

The invention will be further described by way

2

of example with reference to the accompanying drawings, in which:

Figure 1 is a general perspective view showing the complete layout,

Figure 2 is a detail showing the paper control,

Figure 3 is a general perspective view showing the perforating machine,

Figure 4 is a section through the perforating machine,

Figure 5 is a further section through the perforating machine,

Figure 6 is a view in longitudinal section of the punch,

Figure 7 is a transverse cross section through the punch,

Figure 8 is an exploded view of the coupling.

As Figure 1 shows, the complete layout consists of a worktable 1, a driving motor 11, and a perforating machine 13, which is guided by hand.

The frame of the table carries on two opposite sides troughs 2 and 2' for holding and receiving rolled up perforation paper 3 before and after perforation. The paper drawn from the roll 3 is drawn tightly over the table top 4. Springs 5 (Figures 1 and 2) which are fixed on to rails 6 and 6' press the paper down on the edge of the table top. By this means the paper is held tight and always lies smoothly on the table top. The rails 6 and 6' which, to facilitate the insertion of the paper, can quickly be lifted out of the grooves 7 and 7' are so shaped (Figure 2) that the paper fragments cut out by the perforation, which occasionally are not picked up by the machine as intended and remain lying on the table top, will fall into the rails 6 and 6' by drawing the paper pattern across the table top and not on to the floor. The rails are then periodically emptied. To protect the table top 4 it should be covered before commencing work with an underlay of stout cardboard 8 which may conveniently be held by pressure-exerting beadings 9 which in their turn are held in clamps 10. The motor 11 is fixed beyond the working surface of the table top 4. By means of a flexible shaft 12, said

motor 11 drives the hand-guided perforating machine 13. Alongside the flexible shaft 12 runs an insulated electric lead 14 which supplies a lamp 15.

When doing perforating, the machine 13 is pushed by hand over the paper along the lines drawn on the paper pattern. The manner in which the machine works will be seen from Figures 3 to 8. It rests at the back on two solid feet 16 (Figure 3—only one foot being visible in this view) and in front primarily on a switching

foot 17 (Figure 4) provided with teeth on its underside. The foot 17 is fixed swingably on a lever 19 by means of a bolt 18. The lever 19 is itself in turn swingably attached to the bolt 20. A spring 21 pulls the foot 17 over by means of a loop 22, also moving a switching crank 23 which simultaneously causes the lever 19 to rest with its free end on a first cam, denoted 24 in Figure 4. The front of the foot 17 rests against a sprung pin 25 which can be adjusted longitudinally by an adjustment screw 26 according to the desired distance between the perforations to be stamped out of the pattern. The adjustment screw 26 is secured against involuntary movement by a spring 27 and a pin 28. The switching crank 23 grips with its deflected end 23' under the nose of a switching ring 29 and holds a coupling or clutch means (Figure 8) in the disconnected position. If the machine is now pushed forward the foot 17 will, as a result of the teeth on its underside, catch in the paper pattern and consequently swing backwards round the bolt 18 whereby it brings the switching crank 23 over the adjusting screw 26 and just far enough for the bent end 23' to release the nose of the switch ring 29. The coupling is thereby engaged and sets the striking mechanism (described later) in motion. At the same time the cam 24 revolves in the direction of arrow R (Figure 4). The lever 19 which is under pressure from the spring 21, turns as soon as the flattened part of the cam 24 passes at its free end in direction of arrow R1 round the bolt 20 whereby the bolt 18 and therewith the foot 17 are raised. The front part of the machine 13 comes thereby to rest on surface 31 and the foot 17 rises to a certain extent from the paper pattern so that the spring 21 can again pull it forward into its original position as far as the stop pin 25. The switching crank 23 thereby also revolves so that it again grips under the nose of the switching ring 29 with its deflected end 23' and disengages the coupling. This cycle of events repeats itself as long as the machine 13 is being pushed forward. By altering the adjusting screw 26 and thereby the stop pin 25, the stroke of the foot 17 is changed and thus it becomes possible to vary the distance between the perforations to be made in the pattern.

If numbers and the like are to be punched in the pattern this can be done free hand, i. e., it is unnecessary to push the machine along previously drawn lines. When doing so the switching of the coupling must, however, not be done by forcing same by means of the foot 17, and a lever 32 (Figure 3) is therefore set upwards, whereby a lever 33 (Figure 4) in the interior of the machine which is connected with the lever 32 by a shaft moves downwards with its free end and presents a firm stop to the pin 34 or the foot 17 so that the latter cannot perform any further switching movement. The foot 17 is thereby pressed sufficiently far forward to cause it to become raised so that the toothed portion of the underside thereof ceases to make contact with the paper pattern; thus the machine can now be easily moved in all directions.

The engagement follows thereby through a further lever 35 (Figure 3) which by being pressed down immediately presses against a projection-stop 23'' (Fig. 3) on the switch crank 23 (Figure 4), allowing the switching ring 29 to rotate continuously by moving the end 23' of the crank 23 out of range of the nose of said ring.

The striking mechanism already mentioned is actuated by a second cam, denoted 36 in Figure

5, cam 36 being situated beside cam 24 and firmly connected with same by a pin 52 (Figure 4). On every revolution of the cam 36 a stroke is performed. In Figure 5 the lever 37 fixed on a shaft 40 has already arrived at the protuberance on the cam 36. It has thereby also raised a striking lever 38 fixed on the shaft 40 and put a spring 39 in tension. When the cam 36 now revolves in the direction of arrow R, the lever 37 flies off the protuberance on the cam 36 and the tightened spring 39 which grips the lever 37, drives this and thereby also the striking lever 38 around to the left, and knocks a perforating punch 41 into the paper pattern. An adjusting screw 42 which is fixed in the lever 37 and presses against the striking lever 38 is so adjusted that the perforating punch does not touch the paper pattern until the lever 37 and thus the spring 39 gripping the latter meet a firm stop. The swing of the striking lever 38 drives the perforating punch into the pattern just so far that a contact screw 44, which is vertically adjustable and set approximately paper thickness from the cutting edge of the perforating punch, rests on the paper. A spring 55 secures the contact screw 44 against involuntary movement. The spring 45 which is thereby slightly expanded immediately brings the lever 38 back to the adjusting screw 42, serving as a stop. This arrangement is made in order that the perforating punch 41 shall remain in the paper only for the briefest possible moment and also so that it shall not tear same by the continuous forward push. For this purpose a catch 45' (Figures 5 and 6) in which the perforating punch 41 is fastened, is revolvingly fixed in the striking lever 38 by means of a bolt 46 and in such a manner that it can swing out backwards. A spring 47 presses the catch 45' on to a stop screw 48 (Figure 7) so that the perforating punch always stands vertically on the paper surface. According to how the perforating punch is formed it will make round, long or square holes or any other form desired, such as letters and numbers. The pieces of paper punched out work upwards inside the perforating punch 41 and work themselves out through the hole drilled through the catch 45', falling into the hollow striking lever 38 to leave same again by 38' whence they are received by a container placed on the outside of the machine. The spring 39 engages on a crank 49 (Figure 5) which by means of the lever 50 (Figure 3) can be turned in order to give the spring 39 a greater or smaller amount of pre-tension according to the thickness of the paper to be perforated. The perforating machine as already mentioned, is driven by a flexible shaft 12 and then through a worm 54 and worm wheel 51 (Figure 5). On the shaft 60 of the worm wheel are fixed beside each other cam 36, cam 24 and clutch ring 29. The cam 36 and the cam 24 are connected by a pin 52 (Figure 8). A spring coil 53 grips with the end 53' in a slit 24' in the cam 24 and with the other end 53'' in the slit 29' in the clutch ring 29. In the engaged position, the coupling draws itself tight on the shaft 60 of the worm wheel 51 and carries with it the parts to be driven. When disconnecting the coupling the clutch-ring is, as already mentioned held fast. The fixing of the cam 36 at an angle to the clutch ring 29 has the effect that when the clutch ring 29 is held fast, shortly before the first segment 36' (Figure 5) of the cam 36 comes to a standstill, the lever 37 revolves a little further by the impetus which the cam still has after being dis-

engaged so that said lever 37 can drop into the first segment 36' of the cam 36. The spring coil 53 is thereby expanded and lifts from the shaft of the worm wheel 51, so that no further carrying along can take place. When re-engaging the coupling the clutch ring 29 is then again fixed whereby the spring coil 53 as a result of its tension again grips firmly on the shaft of the worm wheel and carries along the parts which are to be driven.

I claim:

1. A perforating machine of the type guided by hand over a stationary pattern including a driving motor, a constantly revolving shaft driven by said motor, punch means for effecting penetration of said pattern, a spring disposed so as to be capable of imparting striking motion to said punch means, a cam mounted on said shaft and effective to control the movement of said punch means, and clutch means adapted to cause said cam to rotate with said constantly revolving shaft, there being provided a pivotally mounted lever, the free end of which is adapted to follow the movement of said cam and in so doing to tension said spring prior to actuation of said punch means.

2. A perforating machine of the type guided by hand over a stationary pattern including punch means for effecting penetration of the pattern, a constantly revolving shaft, a pivotally mounted serrated foot, the serrations of which are adapted to engage the pattern surface and to be held whilst moving the machine across the pattern, a first cam mounted on said shaft and effective to raise the serrated foot and return same to its original position after one complete revolution of said shaft, a second cam mounted on said shaft, connected to the first-mentioned cam, and controlling the movement of said punch means, a switching ring also mounted on said shaft, a switching crank cooperatively associated with said switching ring, the latter normally being prevented by said crank from rotating with said shaft and thereby also preventing said cams from rotating with said shaft, a spring adapted to actuate said punch means, a pivotally mounted lever adapted to follow the movement of said second cam and in so doing to tension said spring, movement of said machine across said pattern causing said switching crank to move to such an extent that said switching ring is released and said cams are firmly connected with said shaft so as to rotate therewith, further rotation of said second cam releasing said pivotally mounted lever and hence allowing said spring to cause said punch means to penetrate said pattern.

3. A perforating machine as set forth in claim 2 including adjustable stop means for limiting the angular movement of the serrated foot, whereby the distance between successive perforations in the pattern may be adjusted.

4. A perforating machine as set forth in claim 2 including a spring coil mounted on said re-

volving shaft, said coil being adapted to effect coupling between said first and second mentioned cams, one end of said coil being caused in the coupled position to engage said first-mentioned cam, the other end of said coil being similarly caused to engage said switching ring, said coil thus firmly gripping said shaft whilst in the coupled position, said coil being caused to spread out so as to effect disengagement of the switching ring and said first and second-mentioned cams on movement of the switching crank to prevent rotation of said switching ring and through prevention of movement of said second-mentioned cam against the direction of rotation by means of said pivotally mounted lever.

5. A perforating machine as set forth in claim 4 including a stop pin carried by said serrated foot, a manually operable lever adapted to engage said stop pin to urge said foot out of contact with the pattern, and thereby prevent further movement of said foot, and a further manually operable lever adapted to move said switching crank out of range of said switching ring, whereby by automatic operation of said machine controlled by the forward movement thereof is prevented, and the punch means are actuated periodically by said second cam, in dependence upon the speed of said rotating shaft.

6. A perforating machine as set forth in claim 5 in which the spring means urging the punch means towards the pattern may be adjusted to vary the punching force, the adjustment being effected by means of an externally situated manually operable lever.

7. A perforating machine as set forth in claim 6 in which said punch means comprises a punch carried by a striking lever, said adjustable spring means being adapted to apply force to said striking lever only as far the the surface of the pattern, and immediately to return to its initial conformation, penetration of the pattern being effected by the momentum of said punch.

8. A perforating machine as set forth in claim 7 including also stop means to limit the penetration of the punch so that the pattern is only just penetrated.

9. A perforating machine as set forth in claim 8 in which said striking lever has rotatably mounted therein a catch, a leaf spring, and a hinge pin, said hinge pin securing said catch to said striking lever in such a manner that it can move in a backward direction against the action of said leaf spring.

KARL NICOLAY.
